OF 10,000

No. 10,009.

May 29- 1877

UNITED STATES PATENT OFFICE.

FRANK E. ALLEN, OF YONKERS, NEW YORK, ASSIGNOR TO THE ROXBURY CARPET COMPANY, OF BOSTON, MASSACHUSETTS.

DESIGN FOR CARPETS.

Specification forming part of Design No. 10,009, dated May 29, 1877; application filed May 16, 1877.
[Term of Patent 3½ years.]

To all whom it may concern:

Be it known that I, FRANK E. ALLEN, of Yonkers, in the county of Westchester and State of New York, have invented a new and original Design for Carpets, of which the following is a specification:

The nature of my design is fully shown in the accompanying photographic illustration.

I claim—

The design for carpets, as shown in the accompanying photographic illustration.

In testimony whereof I have signed my name to this specification in the presence of two subscribing witnesses.

FRANK E. ALLEN.

Witnesses:

C. F. BROWN,
A. E. DENISON.
